UNITED STATES PATENT OFFICE.

WILLIAM N. PARKES, OF BROOKLYN, NEW YORK.

COMBINATION THREAD-DRAWING AND HEMSTITCH SEWING-MACHINE.

1,170,666.

Specification of Letters Patent. Patented Feb. 8, 1916.

Application filed April 19, 1909. Serial No. 490,825.

To all whom it may concern:

Be it known that I, WILLIAM N. PARKES, a citizen of the United States, residing in Brooklyn, county of Kings, and State of New York, have invented a new and useful Improvement in Combination Thread-Drawing and Hemstitch Sewing-Machines, of which the following is a description.

This invention relates to hemstitch sewing machines.

It has for its main object the adaptation of such machines to extract threads from fabrics or articles thereby producing open work and simultaneously therewith to hem-stitch such open work.

It is also an object to so adapt the mechanism for use in combination with the mechanism of a hemstitch machine that threads will be extracted without in any way interfering with the use of a folder or other ordinary attachment to turn the work for a hem, or without in any way interfering with the full performance of the functions of hemstitching.

In the present form of my invention I have adapted it for use in combination with a well known hemstitch machine now on the market, in which the movement of the work reverses once to each third reciprocation of the needle, but it is noted that this kind of a movement of the work is not essential. The invention may be used in combination with various kinds of a stitching and feeding mechanism, and is desirable in any machine where it is desirable to extract threads, and simultaneously therewith do stitching.

Referring to the drawings; Figure 1, is a side elevation of a hemstitch machine, discloses a portion of the invention; Fig. 2, is a partial top plan view of the bed of the machine, parts being removed and broken away for clearness; Fig. 3, is a bottom plan view of the bed of the machine, one of the driving gears being omitted to disclose the cutter oscillating shaft bracket; Fig. 4, is a sectional view of the eccentric by means of which the thread cutter mechanism is operated; Fig. 5, is a like view of the forked arm, which transmits the movement from the eccentric; Fig. 6, is a sectional detail of the bracket on which the thread cutting mechanism is mounted; Fig. 7, shows details of the cutter holder lever, and the arm on which the same is pivoted; Fig. 8, is an enlarged perspective of the thread cutter; Fig.

9, is a cross sectional view of the bed of the machine, with certain parts broken away and other parts omitted to more clearly show the location and arrangements of parts of my device in combination with the mechanism of a hemstitch sewing machine; Fig. 10, is a detail view showing parts in their position when the thread reflector is down; Fig. 11, is a like view of the same parts, when the deflector is free from the goods, and the cutter is about to operate; Fig. 12, is a detached top plan view of the needle-plate; Fig. 13, is a sectional view of the same taken on the lines 13—13, Fig. 12 looking in the direction of the arrow; Fig. 14, is a perspective view of the under side of the needle-plate; Fig. 15, is an enlarged sectional view of the needle-plate, taken on line 15—15, Fig. 12, and Fig. 16, is a detached detail face view of the thread deflector showing the teeth on the same.

In the drawings A represents the arm of the machine, and B the base or bed of the same. In suitable bearings in the arm is mounted the driving shaft (not shown) to the end of which is secured a wheel 1, by means of which power is transmitted to the machine.

In the present form of my invention I have adapted it for use in combination with a usual form of stitch forming mechanism, and feeding mechanism used in hemstitch sewing machines now on the market, and well known.

In the stitch forming mechanism, is a needle bar 2 which is reciprocated in a usual manner from the driving shaft of the machine. To the lower end of said needle bar is secured a bracket 2 1/2 that carries pivoted needle holders 3 and 4, in which are secured needles 5 and 6. On the upper shaft of the machine is mounted a usual form of cam (not shown) by means of which a lever 7 pivoted at 8 is oscillated. In the lever 7 is adjustably secured one end of connections 9 and 10, the other ends 11 and 12 of which are adapted to slide on pivots 13 and 14. The end 11 of the connection 9 carries means for suitably engaging a vertical rod 15, which at its lower end is secured by means of screw 16 in the needle holder 4, and the end 12 of the connection 10, carries suitable means for engaging a vertical rod 17, the lower end of which is secured by means of a screw 18 in the needle holder 3.

In suitable bearings on the under side of

the machine, is secured a shaft 19, which is rotated in a usual manner from the upper or driving shaft of the machine. To the shaft 19 is secured a gear 20 that meshes with a gear 21 that in turn is secured to a suitably mounted short shaft 22. The gear 20 being twice the diameter of the gear 21 it will be understood that the shaft 22 is revolved twice to each rotation of the shaft 19, and the shaft 19 is revolved in unison with the driving shaft of the machine. On the shaft 22 is secured a gear 23 which meshes with a gear not shown, carried by the lower end of a short vertically disposed shaft 24, which latter is mounted in suitable bearings in a bracket 25, adjustably secured by means of screws 26, and slots 27 to the under side of the bed of the machine. To the upper end of the shaft 24, is secured a usual hook or looper 28 provided with a beak 29. On the shaft 22 is secured a second gear 30, which meshes with a gear 31, that is secured to the lower end of a vertical shaft 32, which in turn is suitably mounted in an adjustable bracket 33, that is secured by screws 34 and slots 35 to the under side of the bed of the machine. To the upper end of the shaft 32 is secured a looper 35 1/2 provided with a beak 35 1/4.

30 The gears by means of which the shafts 24 and 32 are rotated from the movement of the shaft 22, are all of the same diameter, consequently the shafts 24 and 32 rotate in unison with the shaft 22.

35 The foregoing stitch forming mechanism, which has been generally described, is of a well known type as before noted, and it is therefore not thought necessary to describe the operation of the same. It *per se* forms no part of my invention but is, in combination with it, a part of the same, and is illustrated here for the purpose of demonstrating that it may be used in combination with the usual stitch forming mechanism of a 45 hemstitch sewing machine.

In the invention as here described, a usual form of hemstitch feeding mechanism is shown, this will now be described in a general way.

50 On the shaft 19, is secured a gear 36, that meshes with a gear 37 secured to a short shaft 38, journaled in a bracket 39, which latter is suitably secured to the under side of the bed of the machine. The gear 37 is three times the diameter of the gear 36, therefore it will be understood the shaft 19 revolves three times to each revolution of the shaft 38. In the side of the gear 37 is formed a cam groove (not shown) which engages in a usual manner an arm 40, secured to one end of a shaft 41, which latter is suitably journaled in a bearing extending from the under side of the bed of the machine. To the other end of the shaft 41, is secured an arm 42 to which is adjustably

connected a pivot 43 on which is journaled at 44 one end of a link 45. The other end of the link 45, is suitably pivoted to an arm (not shown) that extends upwardly from an oscillating shaft 46, which latter is pivoted between centers 47 and 48. To the shaft 46 is secured an arm 49, to the upwardly extending end of which is pivoted one end of a feed bar 50, which at its other end is forked as at 51. The forked portion 51 embraces a shoe 52 carried by an arm 53 that extends horizontally from a shaft 54, that is pivoted between centers 55 and 56. To the shaft 54 is secured an arm 57, which carries a usual anti-friction roller (not shown) that is engaged by a cam 58 secured to the end of the shaft 38. A spring 59, one end of which is secured at 60 to a pin carried by the base of the arm 49, and at its other end by means of a screw 61, to the feed bar 50, serves as a means for normally holding the anti-friction roller carried by the arm 57 in engagement with the cam 58. To the feed bar 50, is secured by means of screws 62, a feed dog 63.

In the foregoing paragraph I have described in a general way the usual form of feeding mechanism used in hemstitch machines. The peripheral cam 58 is so constructed that it gives, through the intermediate mechanism, between it and the feed dog 63, the usual vertical movements to the latter, and the cam groove in the side of the gear wheel 37 is so constructed that it transmits to the feed dog the usual horizontal movements to the same. These movements are so well known that it is not thought necessary to describe them here.

In suitable bearings in the machine is a usual form of presser bar 64, depressed by a usual spring (not shown). This presser bar carries at its lower end a usual form of hemstitch presser foot 65. In suitable bearings (not shown) in the arm of the machine, is mounted a separator bar 66, which carries at its lower end a separator 67. This separator is suitably operated in a usual manner by the usual form of mechanism (not shown) used in hemstitch machines.

To the bracket 2 1/2, is secured a part 68 having a horizontally projecting pin 69 formed on it, on which is secured by screw 70 a thread extractor or deflector carrier 71 provided with a thread extractor 72, having teeth 73 formed on it, and terminating in a needle point 73 1/2, as shown in Fig. 16.

A needle plate 74 is provided with notches 75 and 76, in which, when the parts are in their respective positions, are located tongues 77 and 78, projecting outwardly in a usual manner from bobbin cases 79 and 80. In the said needle plate is formed a needle slot 81, and openings 82 and 83 through which the feed dog operates, and on the under side of said needle plate is

secured by means of screws 84 and 85, a part 86 having a downwardly extending portion 87 and a horizontally extending stem 88. The downwardly extending portion 87 of the part 86 serves the usual function in hem-stitch machines of guarding the needles and keeping them properly separated and in suitable position favorable for loop engagement. Through the needle plate is formed a slot 89, which extends from 90 to 91, see Fig. 15. Along the sides of this slot are formed ledges 92 and 93, on which rests the upper cutter member 94, secured to the needle-plate by means of a screw 95.

15 At 96 the cutter member is reduced in thickness and terminates in a shear edge, as shown at 97 in Fig. 15.

From the needle slot 81, on the under side of the needle plate at 98 is an incline, and 20 from 98 to the end 90 of the slot 89, the needle-plate is of the same thickness as the part 96 of the cutter plate 94. When the cutter plate is in position, a part of the slot 89 indicated by 99, Fig. 12, is exposed and 25 this opening is directly under the thread extractor 72, and forms a passage for the same.

On the end of the shaft 19, is secured an eccentric 100 which operates between jaws 30 101 of an arm 102, that is secured by means of a screw 103 to a shaft 104 mounted on a bracket 105 that is secured to the bracket 25. To the forward end of the shaft 104 is secured an arm 106, in which is secured a 35 screw 107, having an enlarged part 108 on which is pivoted a lever 109. Through the said lever are openings 110 and 111. On the top of said lever, there are ribs 112 and 113 that extend slightly upwardly and between 40 these ribs a cutter plate 114, is located and secured by a screw 115. Through the cutter plate is an opening 116, that registers with the opening 110 of the cutter carrier lever. On the other end of the cutter carrier is 45 formed a stop projection 117 in which is secured a pin 118, to the outer end of which is connected one end of a spring 119, the other end of which is connected to a pin 120 carried by the arm 106. The cutter plate 114 has an upwardly extending part 121 provided with a cutting shear edge 122. The portion 121 of the cutter plate 114 is broader than the opening 99, so that when 50 the machine is in operation, it will ride across said opening without entering the same. The normal strain of the spring 119, turns the lever 109 on its pivot so that the cutter edge 122 of the cutter plate 114, is pressed upwardly, against the under side of 55 the upper member of the cutter device. When the needle-plate is not in position however, then the spring turns the lever 109 a little farther on its pivot, until the stop 117 contacts with the arm 106. It will 60 therefore be understood that the function of

the stop 117 is to limit the movement of the lever 109, when the needle plate is removed for any purpose whatever.

In the operation of my improved machine, the stitching and feeding mechanisms operate as in a usual hemstitch machine, but instead of the usual piercer entering the goods in front of the needles, the thread extractor 72 enters in the same manner except in the present form of my invention 70 it enters a little farther away from the needles than the usual piercer. As the needle bar descends the thread extractor also descends, and presses short ends of the threads, that run in the direction of the feed 80 of the work, down through the opening 99. At this point the part 121, of the cutter member 114, is back of the thread extractor as shown in Fig. 10. The eccentric or cam 100, is so constructed and timed that just 85 after the extractor is withdrawn from the work the lower cutter plate is moved in a direction from the needle across the opening 99, and the short ends of the threads that have been pushed down by the thread extractor, are thereby cut off. It will be observed that the cutter edge 122, of the lower member of the cutter device, and the edge 97 of the upper member of said device, 90 are sheared, so that when the machine is in operation the cutter device shears off the threads that the extractor has pushed down.

The opening 116, through the cutter plate 114, which registers with the opening 110, through the lever 109, and the opening 111, also through the lever 109 serves as passage ways for the discharge of the pieces of threads as they are cut off. And the opening back of the cutter blade to the needle slot as shown in Fig. 15, prevents any clogging of a stray piece of thread back of the lower member of the cutting device. In a full size working machine that I have constructed, I find that these means serve to prevent the cut off ends of the threads from 100 clogging and thereby interfering with the successful operation of the cutter device. I also find in practice that threads cut off pass down through openings 110 and 111. Under 105 these openings any suitable means may be 110 used for guiding these threads to any suitable receptacle that may be provided for the purpose.

The thread separator 67 performs the functions of separating the cross threads 120 of the material just previous to the entrance of the needles, and it also assists in crowding the threads together to form the open spaces and bars, that constitute the open work part of the hemstitching done on this 125 improved machine.

It will be understood that my mechanism as herein disclosed is a preferred form of the same, for use in combination with a double needle hemstitch sewing machine, but I do 130

not wish to be limited to this particular kind of machine, or to the particular kind of mechanism I have disclosed.

What I claim as new is:

5. 1. In combination in a sewing machine, a stitch forming mechanism comprising a needle, means for producing a relative lateral movement between said needle and the work, a fabric thread extracting mechanism the extracting device of which is located to extract threads from the fabric in advance of the stitching and in the direction of the feed of the work, and means for operating said fabric thread extracting mechanism.
10. 2. In combination in a sewing machine, a fabric thread extracting device by means of which ends of one or more threads of the fabric running in the direction of the feed of the work are extracted, a cutter device for cutting off the ends of said fabric threads, and a stitching device adapted to bind or stitch the fabric along the edge of the path from which said fabric threads have been extracted.
15. 3. The combination in a thread drawing and hemstitch sewing machine, of a vertically reciprocating fabric thread extractor, a horizontal reciprocating cutter for shearing off the threads extracted, and a stitch forming mechanism comprising a vertically reciprocating and laterally vibrating needle for making hemstitches or binding stitches along the edge of the path from which the fabric threads have been extracted.
20. 4. In combination in a hemstitch sewing machine, a stitch forming mechanism comprising one or more vertical reciprocating and laterally vibrating needles, a feeding mechanism by means of which the work is advanced once to each third reciprocation of said needle or needles, a fabric thread extracting device, a cutter device, and means for operating said cutter device so that it acts to shear off the ends of the extracted fabric thread each time the needle is reciprocated.
25. 5. In combination in a hemstitch sewing machine having a needle plate or its equivalent, a vertically reciprocating and laterally vibrating needle, an aperture through said needle plate for the passage of the needle, a reciprocating fabric thread extractor located to operate adjacent to the needle and in front of the same, an aperture formed through said needle plate for the passage of the fabric thread extractor, a cutter located below said needle plate to cooperate with said thread extractor, and means for reciprocating said cutter.
30. 6. A combination hemstitch and fabric thread extracting machine comprising a vertically reciprocating and laterally vibrating needle bar, a fabric thread extractor carried by said needle bar, a needle plate, a cutter device having two cutting members, one of said cutting members carried by said needle plate, the other cutting member adapted to reciprocate below said needle plate, and means for reciprocating said other cutter member.
35. 7. A combination hemstitch sewing machine and thread extracting device comprising a cutter device having two cutting members, a needle plate, one of said cutting members attached to said needle plate, an oscillating lever, the other of said cutting members carried by said lever, and a spring connected with said lever by means of which the cutting member carried by it is held into engagement with the cutting member carried by the needle plate.
40. 8. In combination, mechanism for removing body-threads from fabric to produce drawn work; mechanism for hemstitching the work along the thread-drawn line as said body-threads are removed; and means for feeding the work intermittently and progressively up to and beyond both the thread-removing and the stitching mechanisms.
45. 9. In combination, mechanism for removing body-threads from fabric to produce drawn-work; stitch-forming mechanism for hemstitching the work on each side of the thread-drawn line as said body-threads are removed; and mechanism for feeding the work intermittently and progressively up to and past both the thread-removing and stitching mechanisms.
50. 10. In combination, mechanism for removing body-threads from fabric to produce drawn-work; stitching mechanism for stitching the work along the thread-drawn line as said body-threads are removed; and a feeding mechanism including means for intermittently and progressively feeding the work up to the thread-removing and stitching mechanisms.
55. 11. In combination, stitch-forming mechanism; feeding mechanism for feeding the work to and beyond the stitching mechanism; and thread-drawing mechanism, including a reciprocating thread-deflecting blade, a cutter mechanism for cutting the deflected threads arranged between the stitching mechanism and the thread-deflecting blade whereby the threads of the work will be deflected by the blade and carried by the feed into coöperation with the cutting mechanism.
60. 12. In combination, stitching mechanism; feeding mechanism for advancing the work to and from the stitch-forming mechanism; and thread-drawing mechanism, including a thread deflecting device, and a movable cutting-blade, a stationary blade coöperating with the cutting blade; the said thread-drawing mechanism being located in advance of the stitching mechanism, and the feed-dogs of the feeding mechanism being

extended in advance of the thread-drawing mechanism, whereby the work is fed up to the thread-drawing mechanism, the thread is drawn from the fabric and cut, and the fabric then advanced to and from the stitching mechanism.

13. In combination, stitch-forming mechanism; feeding mechanism; and thread-drawing mechanism; the stitch-forming mechanism and the thread-drawing mechanism being arranged one behind the other in the line of feed; and the feeding mechanism including a feed-bar carrying a pair of parallel feed dogs arranged on opposite sides of the stitch forming mechanism and the thread-drawing mechanism.

14. In combination, mechanism for removing certain of the body-threads of fabric; mechanism for gathering in a predetermined manner the remaining body-threads of the fabric at the point where the first mentioned threads are removed, said mechanism being arranged in rear of the thread-removing mechanism; and mechanism for automatically feeding the fabric up to and beyond both the thread-removing and thread gathering mechanisms so that as said threads are removed the remaining threads can be gathered.

15. In combination, mechanism for deflecting certain of the threads of the body-fabric; a stitch-forming mechanism, arranged in rear of the deflecting mechanism, for gathering the remaining body-threads into groups; a thread cutting mechanism arranged between the thread deflecting and stitch-forming mechanisms; and a feeding mechanism for advancing the work to and

from both the thread deflecting and stitch-forming mechanisms, whereby the deflected threads will be carried into position to be removed by the cutting mechanism as a preliminary to the operation of the stitch-forming mechanism.

16. The combination in a thread-drawing and hemstitch sewing machine, of a vertically-reciprocating fabric thread deflector, a cutter for shearing off the deflected thread, and a stitch-forming mechanism comprising a vertically-reciprocating and laterally-vibrating needle for making hemstitches or binding stitches along the edge of the path from which the fabric threads have been extracted.

17. A throat plate having parallel slots for the operation of feed dogs separated by a longitudinal bar, said bar being provided with a longitudinal slot, a blade set within said slot, and means for securing the blade in the slot of the bar.

18. A throat plate, for use in stitching machines, having a feed slot, a needle aperture adjacent said feed slot, and an elongated slot arranged in front of and in alignment with said needle aperture, a cutting blade arranged in said elongated slot, and means for removably securing said blade in place.

In testimony whereof I have hereunto signed my name in the presence of two subscribing witnesses.
